UNITED STATES PATENT OFFICE.

ALWIN W. D. WEIS, OF QUINCY, ILLINOIS.

EGG-SHIPPING PACKAGE.

1,293,589.

Specification of Letters Patent.

Patented Feb. 4, 1919.

Application filed May 8, 1916. Serial No. 96,213.

To all whom it may concern:

Be it known that I, ALWIN W. D. WEIS, a citizen of the United States, residing at Quincy, in the county of Adams and State 5 of Illinois, have invented certain new and useful Improvements in Egg-Shipping Packages; and I do hereby declare the following to be a full, clear, and exact description of the invention, such as will enable 10 others skilled in the art to which it appertains to make and use the same.

This invention relates to the packing of eggs for shipment and storage; and has for its object to produce an improved package 15 for such, and kindred, purposes, with a view to removing certain objections and disadvantages incident to packages now in common use.

The invention is fully disclosed in the description and claim following, references 20 being had to the accompanying drawing, forming a part of this specification, in which—

Figure 1 is a plan view illustrating my 25 improved package, a part of the packing-case cover being broken away to show the contents of the case. Fig. 2 is a side view, a part of the side of the case being broken away, and the upper row of egg-cells being 30 in section to show the eggs in position.

In the drawing I have illustrated a packing-case of familiar construction adapted to hold thirty dozen eggs, and designated by the numeral 1. Cases of this size contain 35 ten fillers 2, five in each end. Between the fillers are placed divider boards 3, of straw-board, or the like, which in the simpler styles of packages are cut nearly as large as each compartment of the case, superficially. 40 Straw, excelsior, or the like, is often placed at the bottom of the case for a cushion, and on that the first divider and filler of the series, with a similar cushion under the cover. The cushion herein shown is a formed 45 cushion of corrugated paper, the bottom and top cushions being alike, and numbered 4. In Fig. 1 are shown the edges of side and end cushions 5, which are the principal features of this invention.

50 It will be understood that the main purpose of the side and end cushions is to protect the contents of the fillers against lateral shocks, which tend to bend or break the narrow ends 6 of the filler strips. These 55 ends are also easily bent or broken in the handling of the fillers, and when broken off,

or bent around sidewise, they become useless in themselves, and instead of preserving a cushioning space between the outer filler strip and the inside of the case, allow said strip to lie against the inside of the case, and breakage of the contents is sure to follow. The side cushions have thus become a practical necessity, though not universally used.

60 The invention is very simple, and consists in providing side cushion strips 5 of practically the same width as the filler strips, and as clearly shown in Fig. 2. These side-strips are interposed between the divider- 70 boards and rest on them, and serve as a part of the support for the board above. They thus help to stabilize and stiffen the package as a whole from top to bottom.

75 A number of advantages are incident to this construction. One of these is convenience in packing. When side cushions as wide as the depth of the case are used some considerable difficulty is experienced in inserting the fillers, layer by layer. If 80 the fillers, with interposed dividers, be first placed in the case, and filled, layer by layer, it is very difficult, if not impossible to slip the corrugated cushions in place between the fillers and the sides of the case. On the 85 other hand, when the fillers and dividers are set in between the cushions, layer by layer, there is considerable difficulty in placing the fillers, owing in part to the inclination of the side cushions to swing inwardly at the 90 top, and in part to the necessity for entering the projecting end of each filler strip in its appropriate groove in the corrugated cushion sheet. As in the case of the ordinary commercial egg-case filler there are twenty eight 95 of these ends to be placed in their proper niches, it will be apparent that the operation is somewhat slow and calls for care and patience. But with the improved cushion strip herein described, the operation may be performed very rapidly, since the filler may 100 first be placed in position, and the strips be then slipped in place, one at a time.

105 A further advantage arising from the use of the improved cushion is that it admits of the use of regular stock fillers and divider-boards, whereas the dividers must necessarily be cut smaller if full-sized sheet cushions are used at the sides. Thus, for example, the packer may have a stock of 110 regular sized dividers and standard spaced fillers, many of which may be faulty in the

matter mentioned above, the ends of the 5 filler strips being broken or bent so as to be useless for protection at the sides. All such fillers would be perfectly usable, however, in connection with side-cushions. But in order to use full-sheet cushions all dividers except the top and bottom in each case must be cut down so as to drop into place between the cushions. With the improved 10 cushion strips, on the other hand, he may use up his stock cleanly and completely, the faulty fillers being reinforced at the sides as fast as they appear, and on as many sides as may be necessary. The same would of 15 course be true in the case of fillers of extra light stock, even though mixed with sound and strong ones. The device thus enables the packer to pack his stuff securely, quickly and easily, without wastage, and without 20 the necessity for re-cutting any part of his material.

The package is designed more particularly for egg shipment and storage, but is appli-

cable to the shipment of other commodities that are liable to break or bruise in transit, 25 such as fruit, glassware, crockery, and the like.

Having thus described my invention, I claim:

A shipping package, comprising: a container, a plurality of cell-cases or fillers fitting therein, top and bottom cushions therefor, dividers of slightly less area than the inside of the case, and side-cushioning strips of substantially the same depth as each filler strip resting on said dividers, the cushioning strips being corrugated to receive the end extensions of the filler strips, and formed to bulge in the interspaces.

In testimony whereof I affix my signature 40 in presence of two witnesses.

ALWIN W. D. WEIS.
